ATTORNEY:

UNITED STATES PATENT OFFICE.

THEODORE W. FOSTER, OF PROVIDENCE, RHODE ISLAND.

DESIGN FOR COVER OF BOXES.

No. 38,182.

Specification for Design.

Patented Aug. 21, 1906.

Application filed July 16, 1906. Serial No. 326,524. Term of patent 7 years.

To all whom it may concern:

Be it known that I, THEODORE W. FOSTER, a citizen of the United States, residing at Providence, in the county of Providence and State of Rhode Island, have invented a new, original, and ornamental Design for the Cover of a Box, reference being had to the accompanying drawing.

The figure in the drawing is the top view of the cover of a box, showing my design.

I claim—

The ornamental design for the cover of a box, as shown.

THEODORE W. FOSTER.
